UNITED STATES PATENT OFFICE

124,819

DESIGN FOR A WATCH BRACELET

Charles H. Kestenman, Providence, R. I., assignor to Kestenman Bros. Mfg. Co., Providence, R. I., a corporation of Rhode Island

Application July 10, 1939, Serial No. 85,936

Term of patent 7 years

To all whom it may concern:

Be it known that I, Charles H. Kestenman, a citizen of the United States, residing in the city of Providence, county of Providence, and State of Rhode Island, have invented a new, original, and ornamental Design for a Watch Bracelet, of which the following is a specification, reference being had to the accompanying drawing, forming a part thereof, in which:

Fig. 1 is a plan view of a watch bracelet showing my new design;

Fig. 2 is an edge view of the same; and

Fig. 3 is a bottom plan view of the watch bracelet.

The dominant feature of my design resides in the diverging strand portions forming the connection between the central bracelet and the end clasps.

I claim:

The ornamental design for a watch bracelet, substantially as shown and described.

CHARLES H. KESTENMAN.
